UNITED STATES PATENT OFFICE.

OMER S. HENDRICKS AND JOHN D. TERHUNE, OF FRANKLIN, INDIANA.

RAIL-JOINT.

No. 800,104.

Specification of Letters Patent.

Patented Sept. 19, 1905.

Application filed December 20, 1904. Serial No. 237,615.

To all whom it may concern:

Be it known that we, OMER S. HENDRICKS and JOHN D. TERHUNE, citizens of the United States of America, residing at Franklin, in the 5 county of Johnson and State of Indiana, have invented certain new and useful Improvements in Rail-Joints, of which the following is a specification.

This invention relates to rail-joints, and more 10 particularly to that class known as "web-block."

The object of the invention is to provide a device of this character that is of novel construction and will effectually hold the opposing 15 ends of rail-sections secured.

It is also an object of the invention to provide novel means in a device of this kind wherein the "knocking" or "pounding" of the rail ends is reduced to a minimum.

20 A further object of the invention is to provide means in combination with the device whereby the invention may be applied and held in position without the use of bolts.

Still further, it is an object of the invention 25 to provide a device of this kind that will be simple in construction, efficient in practice, and economical to manufacture.

With the above and other objects in view 30 the invention consists in the details of construction and in the arrangement and combination of parts to be hereinafter more fully described and claimed.

In describing the invention in detail reference will be had to the accompanying drawings, forming part of this specification, wherein like characters of reference will denote corresponding parts in the several views, and in which—

Figure 1 is a view in perspective and partly 40 in section, showing the invention applied.

Fig. 2 is a fragmentary view in top plan of two rail-sections, showing the invention in position. Fig. 3 is a section on the line 3 3 of Fig. 2. Fig. 4 is a view in perspective of the 45 web-block detached. Fig. 5 is a fragmentary view of a rail-section, taken on the line 5 of Fig. 2. Fig. 6 is a side elevation of a modified form of the invention. Fig. 6^a is a section on the line 6 6 of Fig. 6; and Fig. 7 is a 50 perspective view of the web-block employed in the modified form, the same being detached.

In the drawings, *a* and *b* denote two rail-sections, which have formed in their heads and centrally of the same the depressions or 55 recesses *c d*. The inner end of the bottom of each of the recesses is rounded, as at *e*, Fig. 5.

Interposed between the ends of the rails is the web-block *f*, which conforms to the contour of the rails. Formed at the upper end of the block and centrally of the width thereof are 60 the opposing lugs or extensions *g*, which have the under surfaces of their ends rounded, as at *h*, to fit within the recesses *c d* of the rails. The lugs do not fit snugly within the recesses, but leave the spaces *i*, when assembled, to allow for the expansion and contraction as it 65 occurs.

It is preferable, though not shown, that the block be placed on a cross-tie. It will thus be understood that a train passing over the 70 rail *a* will bear somewhat on the block *f* before entirely leaving the said rail *a* and that the train will bear on the rail *b* before entirely leaving the block *f*. In this way the knocking or pounding of the rails is greatly 75 reduced and the loss for repairs is minimized and the comfort of travel enhanced.

Formed integral with the web of the block *f* are the fish-plates *j*, which extend a suitable distance to either side of the block and have 80 their ends *k* beveled. These plates bear against the web of the rails and rigidly or securely hold the rail ends in position, and thereby obviate the necessity of bolts. The application of the invention is thought to be 85 perfectly apparent to those familiar with the art.

In Figs. 6, 6^a, and 7 is illustrated a device that is similar to the preceding invention, with the exception that the plates 1 are separate from the block 2, and the plates 1 are secured to the rails 3 and 4 by means of the bolts 5, which can be readily understood. The block 2 is also provided with the lugs 6 7, that are adapted to rest or fit within recesses 90 8 of the rail-sections.

The efficiency and many advantages of the invention will, it is thought, be fully understood from the foregoing description, it being noted that all changes may be resorted to that 95 fairly fall within the scope of the claims attached hereto without sacrificing the value thereof.

Having thus fully described our invention, what we claim as new, and desire to secure by 100 Letters Patent, is—

1. In combination with rail-sections having recesses formed in their heads, the inner ends of the bottoms of said recesses being beveled, a block adapted to be interposed between the 105 opposing ends of the rails, said block conforming to the contour of the rail, oppositely-

extending lugs formed at the top of the block adapted to rest within the recesses of the rail-sections, said lugs having their under surfaces at the ends beveled, said lugs being of less length than the recesses, and plates formed with the web of the block and extending to either side thereof, said plates being adapted to engage the webs of the rail-sections.

2. In combination with rail-sections having recesses formed in their heads, the inner ends of the bases of said recesses being beveled, a block adapted to be interposed between the opposing ends of the rails, said block conforming to the contour of the rail, and oppo-

sitely-extending lugs formed at the top of the block adapted to rest within the recesses of the rail-sections, said lugs having the under surfaces of the end portions beveled the lugs being of less length than the recesses.

In testimony whereof we affix our signatures, 20 in the presence of two witnesses, this 12th day of December, 1904.

OMER S. HENDRICKS.
JOHN D. TERHUNE.
